Joseph Roy.

UNITED STATES PATENT OFFICE.

JOSEPH ROY, OF BOSTON, MASSACHUSETTS.

IMPROVEMENT IN MACHINES FOR FORGING HORSESHOE-NAILS.

Specification forming part of Letters Patent No. 58,185, dated October 2, 1866.

To all whom it may concern:

Be it known that I, JOSEPH ROY, of Boston, in the county of Suffolk and State of Massachusetts, have invented a new and useful Machine for Forging Nails or various other articles; and I do hereby declare the same to be fully described in the following specification, and represented in the accompanying drawings, of which—

Figure 1 is a perspective view, and Fig. 2 a longitudinal and vertical section, of it.

In such drawings, A denotes the frame of the machine, which should be properly constructed for supporting the operative parts. B is a post for giving support to the compound die or anvil C, whose upper end is formed with two operative surfaces, a b, one of them being calculated to aid in giving form to one side, and the other being for aiding in giving form to one edge, of a nail. There are also, within the post B, a movable anvil, D, and a cutter, E, they being arranged in front of the stationary anvil, and with respect to each other, in manner as shown in the drawings. The said movable anvil and cutter have vertical motions and intervals of rest given to them at proper times.

The machinery for the accomplishment of such will be hereinafter described.

Two hammers, F G, are arranged over the anvil, one being directly over and to operate with the surface a and the movable anvil D, and the other being immediately over and to operate with the surface b and the said movable anvil. A projection, c, of each hammer is the part which co-operates with the movable anvil D, and for the purpose of reducing the nail-rod, or drawing it out preparatory to the action thereon of the part d of the hammer, and the part a or b of the stationary anvil.

The hammers turn on a common fulcrum-shaft, f, and are operated or thrown upward by two cams, g h, their downward motions being effected by two springs, i i, arranged as represented.

The two cams are fixed on a shaft, k, carrying a pinion, l, which engages with a gear, m, fixed on another shaft, n, on which two cams are fixed, one of such cams (marked p) being exhibited in dotted lines.

The cams p' are for raising two levers, q q', from which springs r r' extend upward to the two longer arms of the hammers F G. Each of such springs is made to encompass a rod, s, extended down from and fastened to the hammer of such spring.

The object of each cam p', the lever q or q', and the spring r r', applied to each hammer, is to check or diminish the force of the blow of the hammer while descending on the thinner or narrower parts of the nail during its formation, the same being to regulate the force of the blow so as to produce an even spreading or draft of the metal.

There is a cam, t, projecting from the inner face of the gear m. It is to operate against a pin, v, extending from a slider, u, carrying a cam, w, formed as shown in Fig. 2. This cam w is for elevating and supporting the chisel E, which may be depressed at the proper time by means of its own weight, or by means of a spring suitably applied to it.

The movable anvil D is forked, so as to span the cam w and rest on the slider u, which has cavities x made in it for the anvil D to drop into at the proper time for it to be depressed.

A spring, y, abutting against a stationary post, 2, acts against a projection, a', (raised upon the slider u,) and serves to retract the slider u, or maintain it in contact with its cams t and o. The latter cam is fixed on the shaft n, and serves to advance the slider u.

There are two pawls, b' c', jointed to the slider u. (See Fig. 2.) These pawls stand at opposite angles of inclination with a rack-bar, H, provided with two racks to receive the pawls.

The teeth of one rack are arranged to stand in directions opposite to those of the other rack. The two racks are shown at d'.

The pawl b', which is a lever supported on a fulcrum, c', operates with one of the racks to maintain the rack-bar H backward, in order to cause the nail-rod to be drawn back over the stationary anvil during the process of drawing out the rod by the hammers. The said pawl b' is thrown into action with its rack by a spring, f', operating against its front arm, said arm being provided with a cam, g', at its front end or part. This cam g', by its action against the shaft n, when forced against

it by the slider u during its advance, will so move the pawl b' as to raise it out of its rack.

During the backward movement of the slider u the spring y will be contracted. As the rack-bar H will move back simultaneously with the slider u , which will be so moved by the cam o , the spring, as soon as the projection h' of the slider u may have passed the extreme point of the cam o , will be set free, and will impel the slider u forward, or in a direction toward the cam o . As the pawl c' will catch in its rack, it will at the same time cause the rack-bar H to advance with the slider u , so as to carry the nail-rod far enough forward and over the anvil D for another nail-rod to be formed from the rod. This anvil is to have a thickness equal to the length of such portion of the nail-rod as may be required for the formation of a nail.

After the formation of each nail, the nail-rod is advanced far enough beyond the cutter to enable the latter to separate the nail from the rod, by a blow of one of the hammers. Immediately after the nail has been severed from the rod the chisel or cutter E is to descend below the working face or top part of the anvil D . Such anvil, after having operated with the parts c of the hammers to properly draw out the nail-rod, is to descend below the working surfaces of the stationary anvil C , in order that the parts d of the hammers may co-operate with the forming-surfaces of the anvil C , and finish the nail or reduce it to its proper shape and size, and form it with a head, such head being made by cavities $i' k'$ in the hammers and the parts $a b$ of the anvil C .

The next part of the machine to be described is that for rotating the nail-rod one-fourth of a revolution at each time, and moving it alternately over the two halves or parts of each anvil.

The rotary motion of the rod is an intermittent one, but is made in one direction.

The said nail-rod is shown at R in the drawings. It extends through and is supported by a shaft, S , which is sustained by a movable box, T , resting on a stationary cross-rail, U , of the frame A .

The box T is held to the rail U by means of a lever, l' , and a parallel link, m' , (see Fig. 3, which is a longitudinal section of the box and its connections with the rail U .) These connections are like the joint-bars of a parallel-ruler, and are for the purpose of not only moving the box T longitudinally back and forth on the bar U , but at the same time of raising it off the bar, in order that the nail-rod may be revolved ninety degrees during each lateral movement of it occasioned by the lengthwise movement of the box.

There is fixed to the shaft S a lantern-wheel, K , having four teeth, n' . With this lantern-wheel one impelling-pawl and one draw-pawl operate, they being shown, at $a' p'$, as jointed to an arm, q' , which is fixed on one end of a shaft, r' , arranged as represented in Fig. 1.

The shaft r' has another arm, s' , projected from it and jointed to a connecting-rod, t' , whose upper end is jointed to a crank, u' , projecting from one end of the driving-shaft k . During each half revolution of the shaft k the nail-rod will be turned ninety degrees.

The longitudinal movements of the box T are effected by the lever l' and by means of a connecting-rod, v' , which is jointed to the longer arm of such lever, and also to the crank q' .

In order that the nail-rod may be further supported and be maintained in parallelism with the axis of the machine while such rod may be in movement, it is carried longitudinally through another shaft, to which it should be clamped by a set-screw or other proper means.

The shaft W is arranged in a horizontal slot, x' , made in a post, w' , projecting upward from the rack-bar H . Furthermore, there is a cam, X , on one end of the shaft W , which, by revolving with the shaft and against a projection, Y , from the post w' , serves to aid in preserving the nail-rod in its proper position, or in parallelism with the axis of the machine, while the said nail-rod may be in the act of being moved laterally and revolved.

A spring, z' , by bearing against the periphery of a circular head, a^2 , fixed to the shaft W serves to move the shaft in a direction opposite to that in which it may be moved by the cam X .

The machine above described, by proper changes of form of the working-faces of its anvils and hammers, may be employed to forge files, pistol-barrels, or various other articles.

It is intended for the formation of articles which have their opposite sides different in form from their opposite edges.

What I claim as my invention in the said machine is as follows:

1. The combination, as well as the arrangement, of the stationary anvil C , the movable anvil D , the two hammers $F G$, and the mechanism for supporting and revolving the nail-rod and moving it lengthwise, as set forth, such movable anvil and hammers being provided with mechanism for operating them, substantially in manner as specified.

2. The combination, as well as the arrangement, of the cutter E with the anvil C , the movable anvil D , the two hammers $F G$, and the mechanism for supporting and revolving the nail-rod and moving it lengthwise, as set forth, such movable anvil, hammers, and cutter being provided with mechanism for operating them, substantially as hereinbefore specified.

3. The mechanism or combination for supporting and revolving the nail-rod and moving it lengthwise, as set forth, the same consisting mainly of the shaft S , the box T , the rail U , the lantern-wheel V , the cam X , the projection Y , the spring z , the head a^2 , the slotted post w' , the rack-bar H , with its toothed racks, the pawls $b' c'$, the slide u , the spring

y, the cam *o*, the shaft *h*, the crank *u'*, the rod *t'*, arm *s'*, shaft *r'*, arm *q'*, pawls *o' p'*, connecting-rod *v'*, lever *l'*, and link *m'*, the whole being substantially as specified.

4. The combination of the cams *p'*, the levers *q q'*, and springs *r r'*, or their mechanical equivalents, with the hammers *F G*, as arranged and combined with the stationary and

movable anvils *C D* and mechanism for supporting and operating the nail-rod, substantially as described.

JOSEPH ROY.
